UNITED STATES PATENT OFFICE.

HUGH SANGSTER AND JAS. SANGSTER, OF BUFFALO, NEW YORK.

LANTERN.

Specification of Letters Patent No. 8,154, dated June 10, 1851.

To all whom it may concern:

Be it known that we, HUGH SANGSTER and JAMES SANGSTER, of the city of Buffalo, county of Erie, and State of New York, have invented an Improved Mode of Constructing Lanterns, of which the following description, taken in connection with the accompanying drawings and references, is sufficiently clear and comprehensive to enable others of competent skill to make and use our invention.

The nature of our improvement consists in providing the lamp with two springs, each attached to its upper part (one opposite the other,) and extending down nearly to the base of the lamp, when each forms an elbow thence passing under the lamp and terminating immediately below it, so as to permit the lamp to be removed from the lantern with ease and facility by pressing horizontally upon the springs.

Figure 1, is a semi-perspective view of the whole lantern. Fig. 2 is a semi-perspective vertical section. Fig. 3 is a bottom view looking upward.

A, is the glass, B, the cap, and C, the ring or bail by which the lantern is carried. The glass is set in the case or frame D, which incloses the lamp F, and the burners H. This frame or case has a circular flange E,

projecting both outward and inward from the base of the case D. The lamp being inserted from the bottom through the circular opening formed by the inner edge of the flange E, passes into the lantern, until another circular flange G, projecting outward from the base of the lamp F, meets the bottom of the case D, or the lower side of E. The elbows of the springs I, at this point come just above the edge of the inner part of the flange E, thence being thrown outward, rest upon the flange and thus secure the lamp in this position. Upon pressing the knobs L toward each other the springs will be brought in contact with the sides of the lamp and permit it to be removed with rapidity and ease, while it is rendered at the same time perfectly secure from being accidentally disengaged.

What we claim as our invention and desire to secure by Letters Patent is—

The mode of attaching the lamp to the lantern by means of the springs and flanges as herein substantially set forth.

HUGH SANGSTER.
JAMES SANGSTER.
